UNITED STATES PATENT OFFICE.

JOHN H. KLEPINGER, OF GREAT FALLS, MONTANA, AND FRANK R. CORWIN, OF DOUGLAS, ARIZONA.

FURNACE-HEARTH.

1,140,042.

Specification of Letters Patent. Patented May 18, 1915.

Application filed December 17, 1914. Serial No. 877,704.

To all whom it may concern:

Be it known that we, JOHN H. KLEPINGER and FRANK R. CORWIN, citizens of the United States, residing, respectively, at Great Falls, county of Cascade, State of Montana, and at Douglas, in the county of Cochise, State of Arizona, have invented certain new and useful Improvements in Furnace-Hearths, of which the following is a full, clear, and exact description, reference being had to the accompanying drawings, forming a part hereof.

Our invention has relation to improvements in hearths for roasting (and other) furnaces; and it consists in the novel features of construction more fully set forth in the specification and pointed out in the claims.

In the drawings, Figure 1 is a middle vertical section through a conventional McDougal roasting furnace showing our invention applied thereto; Fig. 2 is a top plan of one-half of a hearth with central drop holes, with portion of the concrete removed to show the reinforcing members; Fig. 3 is a similar view of one-half of a hearth with circumferential drop holes; Fig. 4 is a vertical cross-section on the line 4—4 of Fig. 2; Fig. 5 is a vertical cross-section on the line 5—5 of Fig. 3; Fig. 6 is a plan of one-half of the bricks or blocks designed to close the central opening of the hearth shown in Fig. 3, traversed by the rabble shaft; and Fig. 7 is an edge view of Fig. 6.

The present invention is primarily directed to hearths of roasting furnaces of the McDougal or circular type (though obviously not restricted either to this type of furnace or to hearths of roasting furnaces specifically) and has for its object (1) to eliminate the high cost of repairs that are always in evidence where brick hearths are in use, (2) to increase the efficiency of the roaster, (3) to effect a ready removal of heavy incrustations which may form on the roofs of the hearths, and (4) to provide a hearth that is practically indestructible.

Up to the present time it has been the general practice to construct these hearths of some form of molded block, usually brick or tile. For the construction of such hearths a number of different forms of brick or blocks are necessary, and the work of installing requires the services of skilled mechanics, all of which materially adds to their cost. Such a hearth being composed of a

large number of integral parts, and depending for its stability upon the keying of the arch, is subject to failure by collapsing in case a small part of it should become loose or fall out. Moreover, the parts of which the hearth is constructed are seldom of uniform size or shape, thus making uneven joints and presenting a rough surface on the face of the hearth. These defects are objectionable since they not only tend to weaken the hearth but to increase the growth of lumps or clinkers on the underside of the hearth at points above the drop holes where hot or partially fused particles of ore are usually projected against it by the current of air or gas passing through the furnace. In the operation of such furnace it becomes necessary to remove these clinkers from time to time, the joints and rough surfaces of the hearth presenting points to which the accretion becomes firmly attached; and often the hearth is damaged in their removal and in time may become entirely wrecked or require extensive repairs.

The improved hearth (and furnace lining if desired) which we propose to construct, is molded into proper form by the use of suitable material such as concrete, formed from an aggregate of sand, crushed slag and cement, and when set or hardened forms a one-piece or monolithic structure practically free from joints or rough and uneven surfaces, and having the necessary openings or drop holes molded in place during construction. The advantages of such a construction will be fully apparent from a detailed description of the invention, herein shown embodied in a roasting furnace of the circular type. In detail the invention may be described as follows:

Referring to the drawings, F represents the furnace, h the several hearths on which the material is treated, the material dropping from the upper hearth successively through the several hearths until it reaches the bottom hearth of the series.

The material treated is stirred and moved along the hearths by suitable rakes 1 carried by the rabble arms 2 which extend over the hearths from the central rotatable rabble shaft S, the rakes moving the material toward the center of one hearth where it discharges through drop holes o onto the hearth beneath, the rakes in the second hearth moving the material toward the circumference.

or radially outward where it discharges through the drop holes σ' onto the next hearth, on which the material again moves toward the central drop holes, and so on 5 through the series, as fully understood in the art.

For our present purpose we may assume that the furnace is provided with a concrete or equivalent molded lining L made either 10 of one piece or of two or more sections (that is immaterial), said lining serving as the support for the several hearths. The hearth is composed of concrete C in which there are embedded above the bottom surface and 15 below the top, series of concentric rings 3, 3, which are tied by radially disposed iron rods 4 whose terminals are hooked over the inner and outer ring of each series respectively. These rings and rods serve as reinforcing 20 members for the concrete; and in practice the hearths are made by first building suitable forms in the furnace, then arranging the reinforcing rods and rings, and when these are in place, pouring the concrete into 25 the forms and smoothing the surface with a straightedge to give the desired thickness to the hearth. After the concrete has set thoroughly, the forms are removed and the hearths are ready for use.

30 As well understood in the art, the centers of the successive hearths are provided with openings for the free passage of the rabble shaft S, these openings on alternate hearths serving usually the purpose of drop holes 35 for the ore being treated, (except where special drop-holes in the region of these openings are improvised for particular reasons, an example of which is shown in the drawings). The central openings of the 40 alternate hearths carrying the circumferential drop holes σ' however must be closed up around the shaft so that the air and gases may pursue their proper circuitous path or circulation through the hearths from bottom 45 up; and in the present embodiment of our invention we cover up these central openings with fire-brick or concrete sector blocks 5 supported at their outer ends on the inclined or conical ledge α bounding the opening, and 50 at their inner ends between the annular ribs t , t , of the ring 6 through which the rabble shaft passes. Of course, and as well understood in the art, these central openings subserve another obvious purpose, to wit, to 55 afford ready access to the shaft at any time, to insert and remove the shaft, the latter being usually provided with T's or other projections to which the rabble arms are secured. By removing the sectors 5, it is obvious 60 that the shaft becomes readily accessible and the hearth proper need not in any wise be disturbed. These sectors 5 may for convenience be collectively termed as the removable section of the hearth, the monolithic 65 feature of which is directed to that portion

over which the charge in the main is distributed during treatment.

In the present embodiment of our invention the hearth is arched, and in order to afford a plane surface of support for the charge, we preferably deposit on the hearth 70 a layer of a suitable filler d, such as lime rock or its equivalent, over the surface of which the lower ends of the rakes 1 freely travel.

In case of a new furnace we may mold the hearths and lining as a unit, but in the case of furnaces already erected, we employ the existing lining (be it of brick, concrete or other material) to support the independently molded hearths formed directly in the furnace in the manner already described. As pointed out above, the invention while specially applicable to the McDougal or circular type of roasting furnace, may with 80 equal propriety be extended to the "straight-line" type without a change of principle. The term "concrete" is here used in its broadest sense as covering a mass formed by concretion or coalescence of separate particles of matter in one body, and not specifically a mass formed by hydraulic cement, sand, gravel or stone, but of course including the latter. The manner of reinforcing the concrete as here shown may likewise be departed from without affecting the 85 nature or spirit of our invention. The monolith feature or unit is to be understood as extending over the whole or a major portion of what constitutes the available hearth 90 surface. This monolith may of course be supported otherwise than by the lining of the furnace.

Having described our invention, what we claim is:—

1. In a furnace, a hearth comprising a concrete monolithic unit extending over the major portion of the hearth area and provided with openings for the discharge of the material treated.

2. In a furnace, a hearth comprising a concrete monolithic unit extending over the area of the hearth and provided with openings for the discharge of the material treated.

3. In a furnace of the character described, a central rabble shaft, a monolithic hearth maintained about the shaft and having a passage-way for the shaft, the walls of the passage being spaced from the shaft, and suitable removable sectors closing said passage around the shaft and supported at one end by the walls of the opening formed in the hearth.

4. In a furnace of the character described, an arched monolithic hearth provided with a central passage-way or opening, series of concentric rings embedded therein at points above the bottom surface and below the top surface respectively, radially disposed rods 120

embedded in the hearth and having their terminals hooked over the inner and outer rings of each series respectively, and means for supporting the hearth at points along 5 the circumference thereof.

5. In a furnace of the character described, a monolithic hearth provided with a central opening bounded by a downwardly inclined wall, said wall forming a ledge for 10 the support of the outer ends of suitable sector blocks.

6. In a furnace of the character described, a monolithic hearth composed substantially of a mixture of sand, crushed slag and ce-

ment in proportions to set and harden, and 15 provided with openings for the discharge of the material.

In testimony whereof we affix our signatures, each in the presence of two witnesses.
